Patented May 26, 1912.

UNITED STATES PATENT OFFICE.

HUBERT HOPKINS, OF MAPLEWOOD, MISSOURI, ASSIGNOR TO MOON-HOPKINS BILLING MACHINE COMPANY, OF ST. LOUIS, MISSOURI, A CORPORATION OF MISSOURI.

RIBBON-REVERSE MECHANISM FOR TYPE-WRITERS AND THE LIKE.

1,027,732.

Specification of Letters Patent. Patented May 28, 1912.

Application filed December 13, 1910. Serial No. 597,091.

To all whom it may concern:

Be it known that I, HUBERT HOPKINS, a citizen of the United States, residing at Maplewood, Missouri, have invented a certain new and useful Improvement in Ribbon-Reverse Mechanism for Type-Writers and the Like, of which the following is a full, clear, and exact description, such as will enable others skilled in the art to which it appertains to make and use the same, reference being had to the accompanying drawings, forming part of this specification, in which—

Figure 1 is a front elevational view, partly in section, of my improved ribbon reverse mechanism; Fig. 2 is a detail view showing a tumbling pawl; Fig. 3 is a sectional view on line 3—3, Fig. 1; Fig. 4 is a sectional view on line 4—4, Fig. 3, and Fig. 5 is a side elevational view showing the actuating pawl.

This invention relates to a ribbon reverse mechanism for typewriting machines, calculating machines, and devices of similar character where the type make a printing impression on paper usually carried by a platen through an inking ribbon by virtue of an impacting blow thereagainst.

My present invention consists in means whereby a master wheel constantly driven in one direction, step by step, has conjoined to it an arm carrying a double pawl which co-operates with ratchets mounted on independent shafts geared to drive the ribbon spools in opposite directions whereby, when one of said ratchet wheels is driven, one spool will wind up the ribbon, tension upon the ribbon causing the pawl to engage the other ratchet wheel and operate the other spool to wind the ribbon thereon. The tension on the ribbon may be occasioned by the ribbon being completely unwound from one spool to which it is connected, or there may be other causes, such as a twist in the ribbon which prevents it from passing through the guides which are usually provided therefor.

In the drawings, 1 indicates the frame of the machine, and 2 and 3 are spool-supporting spindles or shafts carrying the ribbon winding spools 2^a and 3^a, respectively.

4 is the ribbon. The lower ends of the shafts 2 and 3 carry miter-gears 5 and 6, with which mesh miter-pinions 7 and 8 respectively, said pinions being mounted upon alined shafts 9 and 10. The shaft 9 is

preferably mounted in an elongated bearing 11, so as to give it ample support, its inner end carrying a ratchet wheel 12 whose hub portion extends therebeyond, as shown in Fig. 4, so as to provide a bearing for the inner end of shaft 10 which is supported thereby.

13 is a companion ratchet wheel arranged adjacent the ratchet wheel 12 and having its ratchet teeth extending in the same direction as the wheel 12. This ratchet 13 is preferably provided with a hub portion which is pinned to the shaft 10, which hub portion forms a bearing for a driving ratchet 14; but it is obvious that the wheel 13 can be mounted directly upon the shaft 10 and the ratchet 14 loosely mounted on said shaft. Ratchet 14 is preferably upon a sleeve 15 which carries an arm 16, the outer end of which arm is slotted to receive two tumbling pawls 17 and 18. These pawls are in the form of diamond-shaped blocks, as shown in Fig. 2, and are connected together so as to rotate in the slot in the arm 16, said pawls being held against the ratchets 12 and 13 by means of a spring 19.

20 is a vibrating arm having a driving pawl 21 held by a spring 22 against the ratchet 14 whereby, when said arm 20 vibrates, the ratchet 14 is rotated step by step 85 and always in the same direction.

23 is a restraining pawl in engagement with the ratchet 14 to prevent backward rotation of the same. The bar 20 is operated from some moving part of the machine, such as the spacing mechanism, in the case of a typewriting machine, or from the operating handle, in the case of a calculating machine, said bar being mounted to vibrate and having proper connection for its operation, in any well known manner. The restraining pawl 23 is mounted upon an appropriate support, preferably a part of the frame of the machine not shown.

In operation, the ratchet 14 is rotated step by step by its pawl 21, and causes the arm 16 to revolve step by step and always in the same direction. When the pawl 18 is in the position shown in Figs. 2, 3 and 4, the step by step movement of its supporting arm 16 will cause it to carry the ratchet 13 with it. The ratchet 13 drives the shaft 10, and through the pinions 8 and 6 the spool 3^a will wind the ribbon thereon. The spool 2^a will permit this, as the pawl 17 will ride 110

over the teeth of its ratchet 12 having engagement therewith. When the ribbon becomes exhausted on spool 2^a, or, for any other reason, a tension is placed on the ribbon, which tension tends to bring the wheel 13 to a position of rest, the constant onward step by step feed of the arm 16 will cause the engaging inner end of pawl 18 to turn upon the ratchet wheel 13 as a fulcrum. 5 The spring 19 will permit the outward movement of pawl 18 to accommodate this rotation or tumbling of the pawl, and as soon as pawl 18 is rotated so that the previously engaging point thereof rides over 10 the teeth of ratchet 13, pawl 17 will be brought into position with its major axis substantially radial to the ratchet wheel 12, is which position pawl 17 will engage the teeth of ratchet wheel 12 and the continued 15 step by step movement of the arm 16 will now drive said ratchet wheel 12. As the wheel 12 is pinned to shaft 3, the spool 2^a will now be positively driven, but in the opposite direction, so as to wind the ribbon 20 thereon. Spool 3^a will now be free to pay out its ribbon, and will continue so to do until tension is placed on the ribbon so as to cause the pawls 17 and 18 to be tumbled and effect a disengagement between pawl 17 and 25 its wheel 12, and a reengagement between pawl 18 and its wheel 13. The opposite drive of the spools 2^a and 3^a is accomplished 30 in the simplest way, as shown in the drawings, to wit, locating the driving pinions on opposite sides of their coöperating miter-gears.

I claim:

1. In a ribbon-reverse mechanism the combination of two spools, means for driving them in opposite directions, said means including two ratchet wheels, conjoint pawls for coöperating with said ratchet wheels, means for imparting to said pawls a step-by-step movement about said wheels, and 40 means whereby, when tension is placed on the ribbon, said pawls are automatically shifted from one ratchet to the other.
2. In a ribbon-reverse mechanism the combination of two ribbon spools, means for 45

driving them in opposite directions, said means including two ratchet wheels arranged side by side, a pair of double-pointed pawls connected together and having their major axes intersecting, and means for imparting to said pawls a step-by-step movement. 55

3. In a ribbon-reverse mechanism the combination of spool-driving mechanism including two ratchets arranged side by side, a pair of tumbling pawls for alternately co-operating with said ratchets, and means for driving said pawls step by step, in one direction about the periphery of the ratchets. 60

4. In a ribbon-reverse mechanism the combination of spool-driving mechanism including two ratchets arranged side by side, independent shafts operated by said ratchets, a pair of tumbling pawls for alternately coöperating with said ratchets, means for driving said pawls step by step, and 70 means for holding said pawls yieldingly in coöperative relation to said ratchets.

5. In a ribbon-reverse mechanism the combination of a master wheel, a slotted arm carried thereby, a pair of tumbling pawls rotatively mounted in the slot of said arm, a spring connected therewith for holding said pawls in operative position, a pair of ratchets with which said pawls coöperate, and spools driven by said ratchets. 75

6. In a ribbon-reverse mechanism the combination of a pair of ratchets arranged side by side, two alined shafts on which said ratchets are fixedly mounted, a master driving-wheel loosely mounted on one of said shafts, an arm carried by said wheel, and pawls carried by said arm for alternately engaging said ratchets when tension is placed on the ribbon to reverse the feed of the ribbon. 85

In testimony whereof I hereunto affix my signature in the presence of two witnesses, this 29th day of November, 1910.

HUBERT HOPKINS.
